EAR RING HOLDER

Laura I. White, 321 N. Garfield,
Alhambra, Calif. 91801

Filed Dec. 21, 1970, Ser. No. 26,605

Term of patent 3½ years

Int. Cl. D3—99

U.S. Cl. D86—10

FIG.1

FIG. 1 is a front perspective view of an ear ring holder showing my new design;

FIG. 2 is a rear elevation thereof;

FIG. 3 is a side elevation thereof; and

FIG. 4 is a top plan view thereof.

I claim:

The ornamental design for an ear ring holder, substantially as shown.
